UNITED STATES PATENT OFFICE.

DAVID A. HOOVER, OF PORTLAND, INDIANA.

OIL-BURNER.

1,111,834.

Specification of Letters Patent. Patented Sept. 29, 1914.

Application filed January 10, 1914. Serial No. 811,287.

To all whom it may concern:

Be it known that I, DAVID A. HOOVER, a citizen of the United States, residing in the city of Portland, in the county of Jay and

5 State of Indiana, have invented certain new and useful Improvements in Oil-Burners, of which the following is a full, clear, and comprehensive specification and exposition, being such as will enable others to make and 10 use the same with exactitude.

This invention relates to fuel-oil burners, the same being particularly adapted for cooking-stoves or ranges.

The object of my present invention, 15 broadly speaking, is to provide an oil-burner which will be strong and durable in construction, easily operated and controlled, capable of developing a maximum of efficiency in practice, adapted to consume a 20 minimum of fuel in operation, and which can be manufactured and sold at a comparatively low price.

The more distinctive objects of this invention are: the provision of an oil-burner 25 having a plurality of combustion points with means for the delivery of the gaseous fuel thereto whereby the various flames will be equal in capacity and intensity with relation to each other; to provide a generator 30 for developing gas from the liquid fuel; to provide a controller or damper for regulating the delivery of air to the combustion points; and to provide a substantial base by which the burner will be retained in proper 35 position.

Other objects and particular advantages of my invention will be brought out in the course of the following description.

The preferred manner for the construction 40 of my invention is shown in the accompanying drawings, in which—

Figure 1 is a side elevation of the invention complete. Fig. 2 is a central vertical section taken through the construction 45 shown in Fig. 1. Fig. 3 is a top plan of the body portion, partly in section, taken on the line 3—3 of Fig. 1. Fig. 4 is an inside plan view of a portion of the bottom of the base, as taken from the interior of the air-chamber. Fig. 5 is a cross section, as taken on 50 the line 5—5 of Fig. 1, and Fig. 6 is a perspective detail view of one of the deflectors, and a portion of the generator pipe.

Similar indices denote like parts through 55 out the several views.

In order that the construction, the opera-

tion, and the advantages of my invention may be better understood and appreciated I will now take up a detailed description thereof in which I will set forth the invention as comprehensively as I may. 60

Referring now to the drawings in detail, letter A designates the body-plate, the same being oblong in shape, and having a flange a extending up entirely therearound from its edge, and a like flange a' extending down entirely therearound from its edge. Extending across the upper face of the plate A are the flanges a'' and a''' which correspond with the flange a. 65

Adjoining the inner edges of the flanges or ribs a'' and a''' are the respective air supply cones B and B' which slope upward and with comparatively large apertures b and b' formed through their center, as shown in 70 Fig. 3. Extending longitudinally of the plate A and dividing said apertures b and b' each into two parts are the respective webs b'' and b''', which are located at the 75 bases of the burners.

Letter C denotes the air-chamber, which is in the nature of box-like structure having side and end walls and a bottom, and being of such dimensions that the upper edge will fit around in the flange a' as shown, with the 80 plate A forming the top of the air-chamber. Formed through the center of the bottom of the air-chamber is an aperture x for the admission of air into the air-chamber. 85

Letter D denotes a damper, which is 90 merely a flat plate adapted to slide on the bottom of the chamber C, and when in one position it will close the aperture x. Secured to one edge of the damper D is the rod d which extends out through an aperture in the wall of the air-chamber and provides means for operating the damper from 95 outside the air-chamber.

Extending upward from the center of the outer end of the plate A is a hollow or channeled standard E. And extending up from near the inner end of the plate A is the supporting standard F, in the fork of which may rest the inner end portion of the generator pipe 1. Threaded onto the outer end 100 of the generator pipe is the angular fitting 2, which extends down through the channel of the standard E and then outward to one side as indicated. 105

Numeral 3 denotes a conveyer pipe which 110 is connected to the lower portion of the fitting 2 from which it projects outward to

near the edge of the plate A and then extends along the edge of the plate A to near the center thereof, and then turns inward or centerward. Secured on the inner end of the pipe 3 is the T-fitting 4 which is located at the center of the plate A.

Extending from the T-fitting 4, parallel and in alinement with each other, are the two burner-pipes 5 and 5', the same being equal with each other in length, and they are located directly below and parallel with the pipe 1. Closing the ends of the pipes 5 and 5' are the respective caps 6 and 6', said caps being located near the respective standards F and E. It will be observed that the pipes 5 and 5' rest on the respective webs b'' and b''', there being notches formed in the air supply cones B and B' in which said pipes rest as is indicated. An aperture or vent z is formed in each of the pipes 5 and 5', the same being directed directly upward, as shown, and they are located concentric with the respective apertures b and b'.

Slidably mounted on the pipe 1 are the two round deflectors 7 and 7', each of said deflectors has a recessed lower face which is formed by a peripheral flange or lip y, through which lip are formed a plurality of notches v. Said deflectors are adapted to be located above and concentric with their respective apertures z, as shown in Figs. 1 and 2. Attached to the inner end of the pipe 1 is the elbow 8.

Numeral 9 denotes the controller valve. Connecting the valve 9 with the elbow 8 is the pipe 10. Numeral 11 denotes a portion of the oil supply tank, which is connected to the valve 9 by the pipe 12, as is indicated in Fig. 1.

Modus operandi: Suppose now that the burner be located inside the fire-box of a stove or the like, with the bottom of the chamber C resting on the stove-grate in such manner as to allow air to pass up through the stove-grate and through the aperture z, when it is open. The tank 11 should be placed at a distance from the burner and then connected to the burner, substantially as shown.

Now if the valve 9 be closed and the tank 11 contains a supply of oil, the operation well be substantially as follows: The valve 9 may be slightly opened, allowing a small amount of oil to escape through the apertures z and adhere to the burner pipes 5 and 5'. The valve should then be closed and the escaped oil may then be lighted and the heat rising therefrom will heat the pipe 1, after which the valve may again be opened, thereby causing the pressure to force the gas out through apertures z. The heat from the escaping gas forming a flame will so heat the pipe 1 that the oil as it enters therein will be converted into gas, whereby as soon as the burner is properly heated the discharge

from the vents z will be in gaseous form, which gas will continue to be generated as long as the burner is kept lighted and in operation. The proper combustion may be obtained by regulating the supply of air to the burners, that is by manipulating the damper D as required.

It should be observed that the delivery of the fuel to the burners is such that the flames be of equal intensity; also the entrance of the fuel to the burner pipes is located at a maximum distance from the flames, thereby preventing the joints from becoming loose on account of the heat, which has heretofore been a source of much trouble in burners of this general character.

The construction of the lower faces of the deflectors is such as to cause the flame to concentrate therein and then be deflected out through the notches v in fine streams, which will cover a large amount of surface to be heated thereabove.

Attention is called to the fact that the burner pipes and the generator pipe, which are connected together, are retained securely in operative position by the means set forth, yet they may be easily lifted from the body of the burner after being disconnected from the tank.

The deflectors may be rotated on the generator pipe, in order to place their under faces at an angle, in place of parallel with, the surface of the plate A, in order to deflect the heat more forward or rearward in the stove in which the burner is employed.

I desire it to be understood that this invention is not to be limited to two flames, as herein provided, it being understood that a greater number of flames may be provided for if desired.

I desire that it be understood that various changes may be made in the several details of construction, from that herein set forth, without departing from the spirit of my invention and without sacrificing any of the advantages thereof.

Having now fully shown and described my invention, what I claim and desire to secure by Letters Patent of the United States, is—

1. An oil-burner consisting of a body-plate having air apertures therethrough, an air chamber located below the said plate, means for controlling the admission of air into the said air chamber, a generator-pipe extending across longitudinally of and above the said plate, means for removably securing the generator pipe above the plate, a plurality of burner-pipes located below the generator-pipe and parallel therewith and in alinement with each other, means interiorly connecting the inner ends of the burner-pipes with one end of the generator-pipe, means for connecting the other end of the generator pipe to the fuel supply, and

a valve for controlling the admission of fuel to the generator-pipe.

2. An oil burner consisting of a body-plate having air supply cones extending upward therefrom for the admission of air from below, a generator pipe extending longitudinally of and located above said plate, means for retaining the generator pipe in position, burner-pipes each having an exit 10 therein and located below the generator pipe and parallel therewith, and resting in notches formed in the upper edges of the said air supply cones and with each of said exits concentric with one of the said air 15 supply cones, an air chamber located below the said plate and common to all of the said air supply cones, means for interiorly connecting the inner ends of the burner-pipes with one end of the generator-pipe, means 20 for connecting the other end of the generator-pipe to a fuel supply, a valve for controlling the admission of fuel, and a damper for controlling the admission of air into the said air chamber.
- 25 3. An oil burner consisting of a body-plate having air apertures therethrough for the admission of air from below, a generator-pipe extending longitudinally of and located above said plate, standards for retaining the generator pipe in operative position, burner-pipes located on said plate and located directly below and parallel with the generator pipe, there being an exit aperture in each of said burner pipes, the same 30 being located concentric with their respec- 35

tive air apertures in the plate, means connecting the inner ends of said burner pipes to one end of the generator pipe, an air chamber located below the body-plate, there being a central aperture in the bottom of 40 said chamber, and a damper for opening and closing said aperture in the air chamber.

4. An oil burner consisting of a body-plate having air apertures therein for the admission of air from below the plate, a 45 generator pipe located above and disposed centrally and longitudinally of the plate, burner pipes located between the generator pipe and the plate and parallel therewith, there being an exit from each of the burner 50 pipes, each exit being concentric with one of said air apertures in the body plate, means for connecting the inner ends of the burner pipes to one end of the generator pipe, an air chamber located below said body plate, 55 deflectors slidably suspended on the generator pipe and each being adapted to be located above one of said exits, a lip formed around the edge of the lower face of each of said deflectors, there being a plurality of 60 notches formed in each of said lips, and means for retaining the generator pipe and the burner pipes in operative position.

In testimony whereof I have hereunto subscribed my name to this specification in 65 the presence of two subscribing witnesses.

DAVID A. HOOVER.
